UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed March 3, 1919, Serial No. 280,394. Renewed October 28, 1926.

My invention relates to mining apparatus. It has for its object to provide an improved supporting means for mining machine mechanism whereby the latter is enabled to be operated under a wider range of service conditions and with increased facility. A further object of my invention is to provide an improved supporting and transporting means for such a mechanism, preferably of the swivel tilting front type, which is built close to the bottom and adapted to enable the same to be used in low vein work. A still further object of my invention is to provide an improved supporting means having improved, preferably automatically controlled, supporting mechanism adapted to rest upon the bottom and support the cutting mechanism over the mine bottom, as when operating in a room or an entry. A still further object of my invention is to provide an improved supporting means of the character set forth which is operative to support the cutting mechanism on an uneven bottom, the effective height of the supporting means preferably being automatically variable in accordance with the variations in the level of the mine bottom. Additional objects of my invention include the provision of an improved truck, constructed and equipped to facilitate and speed up the unloading and loading operations of a room and filler machine and the corresponding preliminary and final operations of machines of the type which cut while on the truck, at the same time that an improved, simplified, and rugged construction adapted to function efficiently under the varying stresses and abuses of service is produced. These and other objects and advantages of my improved construction will, however, hereinafter more fully appear.

In the accompanying drawings I have shown for purposes of illustration three embodiments which my invention may assume in practice.

In these drawings,—

Fig. 1 is a plan view of one embodiment of my improvement, the machine being removed to facilitate illustration and the tilting member tilted.

Fig. 2 is a side elevation of the same, the parts being shown in full lines in transport

position and in dotted lines in unloaded position, the machine being removed in the latter position.

Fig. 3 is an enlarged detail plan view, partially in section, showing my improved supporting mechanism.

Fig. 4 is a vertical sectional view taken on line 4—4 of Fig. 3, illustrating the same mechanism and also its operating means, the parts being shown in two positions.

Fig. 5 is a transverse sectional view taken substantially on line 5—5 of Fig. 2.

Fig. 6 is an enlarged detail view of a portion of the swivel support.

Fig. 7 is a diagrammatic view showing this embodiment of my invention in its usual positions in room or room neck work.

Fig. 8 is a side elevation of a modified form of my invention.

Fig. 9 is a side elevation of a further modified form of my invention wherein the same is embodied in a mounted cutter machine.

Fig. 10 is a plan view of the machine supporting means shown in Fig. 9, the machine being removed.

Figs. 11 and 12 are diagrammatic views illustrating certain of the different positions which a machine of this form may occupy during cutting.

In this illustrative construction, it will be observed that I have shown my improvement applied to a mining machine 1, which, while it may be of any desired construction, is shown herein as of the well known flexible chain feed type, having a flexible feed chain 2 and a rotating driving member 3 therefor, and also having a projecting cutter chain carrying bar 4. This machine 1 is supported upon a track frame 5 which is in turn supported on axles 6 and truck wheels 7 movable over the mine track and operatively connected through a suitable driving connection, as a chain and sprocket connection 8. As shown, this connection 8 is itself adapted to be driven by a similar chain and sprocket connection 9 connected to a transverse shaft 10, herein a part of a usual truck driving mechanism 11 carried on the rear end of the truck, and adapted to be driven in any desired manner from the mining machine, herein through a gear 12 included in the truck driving mechanism and

adapted to mesh with a gear 13 on the mining machine when the latter is in transport position. As usual in this type of machine, an upright chain fork 14 is also provided at the rear end of the truck frame 5 in order to cooperate with the chain 2 during the operation of moving the machine upon its truck.

In the form of my improved construction shown in Figs. 1 to 6, it will be observed that the truck frame 5 is elongated, extending a substantial distance beyond the front truck wheels 8. It will also be observed that the height of the same is substantially that of the axles, the frame being so supported thereon by suitable axle boxes 15 that it is disposed but slightly above the top of the axles with its bottom well below the top of the wheels. As shown, this frame includes a plurality of laterally spaced, longitudinally disposed, flat bottom plates 16 and angle or flanged side members 17, 18, of which the members 17 are disposed in rear of the front wheels 7 and are provided with upstanding flanges, while the members 18 are disposed in front of the front wheels beneath horizontal extensions 19 on the members 17 and are provided with depending flanges. It will also be observed that these elements are rigidly connected transversely at their rear ends by the truck driving mechanism 11 and the axles and axle boxes, and are similarly rigidly connected at opposite ends by a plurality of transverse plates 20 in such a manner as to produce an exceedingly rigid structure forming at its rear end a longitudinally disposed guide for a mining machine and having throughout its length a longitudinally disposed central slot 21 formed between the members 16.

Cooperating with this slot 21 and slidable therein is a reciprocable member 22 (Figs. 5 and 6) having straight sides 23 engageable with the walls of the slot 21, and rounded ends 24, the construction being such that the member 22 may rotate only when opposite slightly larger, curved cut out portions 25 at the front end of the slot 21. This member 22 has fixed to its upper surface a turntable element, herein an enlarged, substantially oblong upper plate 26 of substantially the width of the frame bottom and resting on and slidable over the latter, and also has fixed to its bottom a lower, round plate 27 of but slightly greater diameter than the width of the slot 21, and having its edges disposed beneath the edges thereof. Here attention is also directed to the fact that the plate 26 also has fixed to its upper surface at its opposite sides, a pair of flat, longitudinally extending machine supporting plates 28 disposed in but a slightly higher plane than the plate 26, the construction being such that a machine may be supported on the member 26, herein

resting on the plates 28, and be moved longitudinally with the members 22 and 26 or angularly with those members only when it has been moved sufficiently far forward with the latter to have its rear end clear the upstanding flanges on the members 17, i. e., when the member 22 is brought opposite the cut away portions 25. In this connection, it will be noted that the machine when so rotated is locked against longitudinal movement until the flat sides 23 of the plate 22 are again brought into registry with the slot 21.

Operatively connected to the turntable element, is also improved means for loading and unloading a machine relative to the truck. As shown herein, the transversely spaced plates 28 are provided with downwardly disposed extensions or ears 29 on their front ends, herein disposed in vertical planes, which are pivotally connected, as by transverse pivot pins 30, with the rear ends of depending longitudinally extending flanges 31 formed on a longitudinally disposed machine receiving frame 32. This frame 32 is preferably open at both ends and adapted during loading to receive the machine and thereby be disposed horizontally on the frame 5 beneath the machine, and during unloading to discharge the machine and be tilted thereby about the pivot pins 30 until its front end touches the bottom. As shown, this tilting frame 32 includes a plurality of laterally spaced frame members 33 having flat bottom portions and upstanding flanges or sides adapted to guide the mining machine in its movement, the members 33 being suitably laterally braced where necessary, as by transverse bracing members 34, herein at its opposite ends. In connection with this frame 32, it will also be observed that, for use in loading the machine thereon and angling the frame and machine as hereinafter described, upstanding members 35 are provided on opposite sides of the longitudinal center line of the tilting frame 32, preferably at the rear ends of the flanges 33, adapted to be engaged by the feed member, chain slots 36 therefor being provided herein. It will also be noted that in order that this member 32 and the machine thereon may be moved longitudinally by the machine, the frame 5 is provided with laterally extending feed member engaging hooks 37 at its front end, herein in two disposed on opposite sides of the same.

Cooperating with the above described mechanism, and acting to support the machine when the latter is disposed on the extended front end of the truck, as for instance beyond the end of the track in a room or entry, is further improved mechanism. This mechanism as herein shown includes (Figs. 3 and 4) a plurality of pivotally

6 mounted supporting members 38 pivotally supported beneath the front end of the frame 5 in suitable bearings 39 on the opposite sides of the front axle 6 and extending forward on opposite sides of the machine center line a substantial distance beyond the axle, preferably to a point substantially midway between the ends of the protruding front end of the frame 5. As 10 shown, these members 38 are each provided with a rounded and widened front end 40 adapted firmly to engage the mine bottom at any angle of the members 38 thereto, and with a longitudinally disposed chamber 41 in that end, opening toward the center and having a series of upstanding ratchet teeth 42 disposed longitudinally along the bottom thereof. Cooperating with these teeth 42 is a pair of dogs 43 each having a longitudinally disposed series of teeth 44 meshing with the teeth 42 when the dogs 43, due to the action of gravity, occupy the position shown in full lines in Fig. 4. As shown, these dogs 43 are carried on the opposite ends of a two-part transverse stud or member 45 journaled in bearings 46 in transversely spaced rearwardly extending arms 47 pivotally supported at their front ends on a transverse member or rod 48 and laterally spaced thereon by a spacing sleeve 49. This rod 48 is itself journaled on rearwardly extending parallel arms 50 rigidly connected to the front end of the frame 5.

3 Operatively connected with the members 38 and 47 is an operating member therefor. This member is herein illustrated at 51 as a longitudinally extending member disposed between the opposite pairs of members 38 and 47 and pivotally supported at its rear end on the front axle 6 in suitable bearings 52 located between the bearings 39. As shown, the front end of this member 51 carries a member 53 underlying and adapted to lift a sleeve 54 which houses and serves to connect the inner ends of the two-part stud 45. Also it will be observed that the members 38 carry a transverse rod 55 between their ends, which in turn carries a spacing sleeve 56 and is adapted to connect the elements 38 and 51 and underlie a lug 57 on the member 51 and thereby hold the latter in folded position as hereinafter described. Thus it will be noted that by swinging the member 51 upward to raise the sleeve 54 and release the members 38 and 47, those members may be folded into substantially the same plane in inoperative position (dotted lines, Fig. 4) beneath the truck frame, the members being held in that position by the rod 55. Also, conversely, by then releasing the member 51, the parts may be dropped into supporting or operative position (full lines, Fig. 4) and automatically locked therein by the mutual action of the teeth 42, 44.

As shown, this member 51 is automatically operated as the machine moves relative to the truck 5. More particularly, it will be noted that on its rear end and in rear of its pivot, this member 51 carries a transversely disposed roller 58 journaled in suitable bearings formed in rearwardly disposed extensions 59 on the operating member 51. As shown, this roller 58 is engageable by a bottom cam plate 60 fixed beneath and movable with the plate 24 and having a gradually inclined cam surface 61 formed on its rear end and the rear end of the member 24, and a more abrupt cam surface 61' on its front end. The surface 61 is adapted, when the member 22 is moved rearward on the truck, to engage the roller and force it down in such a manner as to raise the members 51, 38, and 47 to the folded, inoperative position shown in dotted lines in Fig. 4, so that the parts may be held in that position by the engagement of the roller with the under side of the plate 60 and locked in position by means herein-after described before the surface 61' has passed over the roller. It will be noted that, conversely, the surface 61' acts initially to depress the roller 58 when the member 22 is moved forward on the truck, and that the surface 61 then acts as a release surface, the latter as the member 22 moves forward then permitting the roller to swing up to the full line position shown in Fig. 4 and thereby permitting the supporting means to drop into their operative or supporting position in which the parts are locked by gravity. Here, it will also be observed that the movement of the member 22 is so timed with respect to the roller 58 that the supporting means are lowered shortly after the member 22 starts outward, i. e., as the machine begins to unload, and that these means are raised when the member 22 has almost completed its inward movement, i. e., when the machine is practically in transport position.

As a result of the provision of the rod 55 on the members 38 and the lug 57 on the member 51, it will also be noted that a supplementary means is provided to cooperate with the cam surface 60 in holding the members 38, 51 and 47 in their elevated position. Attention is also directed to the fact that through the provision of laterally disposed members 62 on the flanges 31 of the tilting member 32, and cooperating laterally disposed lugs 63 on the members 38, further means are provided to prevent the vibrations arising from rough track, crossings, etc. from causing chattering of the supporting means when the same are in transport position, the members 62 automatically sliding under the lugs 63 as the machine moves toward transport position and before the cam surface 61' has passed the roller 58, in

such a manner as to hold up the members 38, and automatically sliding out from under the same as the machine moves to unloading position, in such a manner as to release the members 38 so that they may drop when the roller is released by the surface 61.

In considering the operation of this embodiment of my invention, and referring more particularly to Fig. 7, which illustrates diagrammatically the usual operative positions thereof, it will be observed that with my improved construction it is possible to unload a room and filler machine from its truck at any desired angle. In considering the operation of the mechanism, let us remember that the machine in its movement about the mine occupies the transport position on the truck shown in full lines in Fig. 2, and that the supporting means are in their "up" or inoperative position shown in full lines in that figure and in dotted lines in Fig. 4. The truck is, as usual, brought into the room under its own power and stopped with the front truck wheels 7 thereof preferably closely adjacent the front end of the track and the front end of the frame 5 extending a substantial distance beyond the end of the track in such a manner as to bring the machine as close as possible to the face before it is unloaded. When the truck has reached the position indicated, the feed chain 2 of the machine is connected between the feed driving sprocket 3 thereof and a point at the front end of the truck in a well known manner, as for instance to one or the other of the laterally extending hooks 37. As a result of this connection, when the chain driving sprocket 3 is rotated by the machine, the latter, with its underlying frame 32 and the sliding swivel carrying member 22, will be fed forward along the chain 2 and relative to the guide plates 16. As the member 22 first moves forward, it will be observed that the cam plate 60 thereof will pass freely over, and yet continue to depress, the roller 58 on the then elevated member 51, and thus serve to maintain the members 51, 38 and 47 in their folded or inoperative position until the member 22 has moved sufficiently forward to pass the cam surface 61 over the roller 58. When this occurs, as it does almost immediately and long before the center of gravity of the machine passes over the front axle, the members 62 on the frame 32 have already released the lugs 63 on the members 38 so that these members and their connected members 51 and 47, due to their weight, are free to drop about their pivots into supporting position, wherein the front ends of the members 38 and 51 engaging the bottom and the members 38 and 47, are locked by the engagement of the dog teeth 44 with the teeth 42 on the members 38. Obviously, after the machine has thus been

provided with stable supporting means, the member 22 is free to continue its forward movement until it reaches the openings 25 in the frame 5, where its further forward movement is arrested by its engagement with the upper transverse tie plate 20. In this position of the parts, it will be observed that the machine is disposed substantially above the supporting members 38, 47 and 51. Obviously, if it is then desired to deliver the machine as usual into sumping position at the right rib, this may be readily accomplished, after releasing the usual friction, by simply passing the chain around a usual swing arm 64 on the front end of the machine and changing the connection of the free end of the chain 2 from its hook 37 to a suitable support disposed adjacent the face, herein a usual take-up mechanism 65 preferably initially placed as shown in its position for the cut across the face. When this has been done, by simply again applying the friction the machine may be swung automatically with its swiveled frame 32, the latter being locked as it moves in such a manner as to cause the front end of the latter to align itself with the take-up and then move forward along the chain and in the frame 32 in such a manner as to tilt the latter downward and bring its front end into engagement with the mine bottom while its rear end is supported on the truck, thereby affording an inclined support over which the machine then slides from the truck onto the bottom in its continued movement toward the take-up. Obviously, the machine may thereafter be sumped in the usual manner. If, moreover, instead of so delivering the machine in a room it is desired to deliver the same at the rib or a point nearer the line of the track, as in an entry, it will be observed that this may be readily accomplished by simply connecting the front end of the chain to a support, in the form of either a jack or a take-up, located at the desired point and then starting the feed, whereupon the machine will be fed off of the truck, if necessary, automatically swinging on its swivel into alignment, and, when it reaches that position, being unloaded from the truck as described above.

It will also be observed that, if desired, the machine may be unloaded at right angles to the track and thereby be utilized in cutting room necks or the like, the chain, after the machine has been moved outward, being simply connected to the desired point and the feed then started, whereupon the machine is swung about its swivel to the desired position and then automatically fed off of the truck. After the machine has thus been unloaded from the truck, it will be observed that whatever the angular position of the tilting frame 32 relative to the track, the frame will continue to occupy the tilting po-

sition relative to the truck shown in Fig. 2, i. e., a position in which it is ready to receive the machine when it is desired to load the same. Before this is desired, and preferably while the room or entry is being cut, the frame 32 is swung into the easiest loading angle with respect to the machine. This, due to the balanced structure, is accomplished by simply raising its front end and, after pushing it around to the desired position, dropping the same. With the frame thus in position, usually pointing toward the left rib, by simply extending the chain 2 back up the tilting member and around the nearest chain fork 36 formed on the rear end thereof, to the chain fork 14 on the rear end of the truck, it will be observed that the machine may be returned to its transport position with great facility, the same under certain conditions being automatically drawn up the tilting frame 32 and with the latter moved into horizontal position on the frame 5, and then swung into registration with the latter and reciprocated therein into transport position without any other attention, the supporting means being automatically raised as the machine approaches transport position in the truck. It may, however, be desirable, as in a usual practice, to facilitate the movement of the machine onto the front end of the tilting member by inserting a jack on the thus connected chain at a point between the front transverse members of the tilting member and removing this jack when the machine first rides up over the front edge of the tilting frame. Here it will, however, be observed that in whatever way the machine is guided onto the tilting frame, the chain, just as soon as the machine and frame reach horizontal position on the truck, acts to swing the same laterally into registry with the rear guide portion of the frame 5, and thereafter slide the parts to transport position therein, the chain being automatically disengaged from the chain fork 36 on the rear end of the tilting frame during the swinging action, i. e., when that chain fork is swung past a line extending from the sprocket 3 through the chain fork 14 on the frame 5.

In Fig. 8 I have illustrated a modified form of my invention, which, while not as satisfactory for certain purposes as the form of the same described above, is adapted to use under certain conditions. In this construction it will be observed that a member 66, herein extending from one side of the machine and movable with the latter, engages with an upstanding cam member 67 of suitable form pivotally mounted at 68 beneath the frame 5 in such a manner as to turn the cam member about its pivot and thereby operate a pivoted rod 69. As shown, the downward limit of movement of this rod is established by a stop 70, and the front end of the rod is pivotally connected at 71 to the upper end of a support 72 pivoted at 73 beneath the front end of the frame 5. In the form illustrated herein, the cam member 67 is provided with a plurality of cam surfaces 74 and 75, of which the surface 74 is adapted to be disposed above the level of the frame 5 when the support 72 is in its full line or operative position, while the member 75 is adapted to be so disposed when the support 72 is in its dotted line or inoperative position. Thus it will be observed that by providing a suitable trough 76 between these members 74 and 75, it is possible to actuate this cam member to raise and lower the support 72 as the machine is loaded or unloaded. Obviously, in the use of this form of my invention, a like arrangement of parts may be provided, if desired, on each side of the truck. Preferably, in this form of my invention the support 72 is also adapted to use on the usual varying mine bottom, by providing the same with a vertically adjustable portion or foot 77 adapted to be held in different positions relative thereto by suitable bolts 78 receivable in holes 79 in the support 72.

In Figs. 9, 10, 11, and 12 I have illustrated a further modified form of my invention wherein the same is adapted to use in connection with that type of machine wherein the mining machine 1 is seated in and removably attached to a horizontally disposed, short, open-ended guide frame 80 which is in turn rigidly connected to the top of an upper, horizontally disposed turntable member 81 rotatable about a swivel 82 on a lower corresponding plate 83 and adapted to be held in any desired position with respect thereto by a pin 84 adapted to be received in a plurality of registering apertures 85 in the plates 81 and 83. Herein, it will also be observed that the plate 83 is reciprocable in suitable guides 86 formed on the frame 5, the same being provided with a depending sliding block 87 engageable with and slideable relative to the guides, all as in a well known manner, to or from cooperative relationship with the truck driving mechanism, i. e., transport position, in which the frame 80 is adapted to be locked by the usual locking mechanism 80', the cooperating truck driving mechanism being essentially the same as heretofore. In considering the adaptation of my improved construction to a machine of this type, it will be understood that the members 38, 47 and their connecting mechanism are substantially similar to the same members described above in connection with the form of my in-

vention shown in Figs. 1 to 6. Herein, however, it will be observed that the member 51, while otherwise also similar, is provided with a plurality of upwardly and rearwardly inclined cam members 88 disposed in rear of the front axle 6 and adapted to be engaged by the sliding block 87 and operated thereby. More specifically, it will be observed that with the parts in their operative or supporting position shown in Fig. 9, the rearward movement of the block 87 toward transport position will depress these cam portions 88 and thereby cause the members 38, 51 and 47 to be elevated or folded as hereinabove described; while when the movement of the machine 1 is reversed these cam members 88 will be released as soon as the block 87 clears the same, and thereby permit the members 38, 51, and 47 automatically to resume their operative position shown. Thus it will be observed that in this form of my invention the moving member itself, herein the sliding block 87 on which the machine is supported during cutting, acts to control the supporting mechanism and hold the latter in inoperative position during transport.

In the use of this form of my invention, it will be noted that upon reaching a place, the locking mechanism 80' is first unlocked and the machine then angled relative to the truck, as shown in Fig. 11, and locked in that position by the pin 84 in order to enable the same to make its sumping cut in an entry. In this position, the sliding block 87 is still over the cam members 88 so that the supplemental supporting means extending beyond the end of the track is not lowered. As, however, the machine, as a result of the usual connections of the feed chain shown, is moved outward in its sumping cut, i. e., from the full line toward the dotted line position shown in Fig. 11, it will be observed that the supporting mechanism is automatically actuated in such a manner as automatically to provide a stable support for the machine well before the center of gravity passes over the center line of the front axle. Conversely, when the machine, as a result of the usual changed connections of the feed chain shown, has made its transverse cut, i. e., moved from the dotted line position shown in Fig. 11 to the dotted line position shown in Fig. 12, and, as a result of the then further changed feed chain connections shown, is moved rearward in its withdrawal cut from the dotted line position shown in Fig. 12 to the full line position shown therein, it will be noted that the block 87 will then engage the cam members 88 in such a manner as to depress the same and thereby fold the supporting mechanism into its inoperative position after the machine has passed off of the overhanging portion of the frame.

As a result of my improved construction shown in Figs. 1 to 6, wherein the machine is supported almost directly upon the axles, it will be observed that it is possible for a combined swivel and automatically tilting front type truck such as is used in a short-wall practice to be adapted to low vein work, in which, on account of its great height, it has heretofore been impossible for any known truck of this type to operate. More particularly, it will be observed that due to my improved construction it is possible to reduce the height of the mechanism by substantially nine inches and thereby produce a mechanism having a height of about thirty-four inches which is amply low to enable this type of truck to be used in any of the many so-called low vein mines which constitute about thirty per cent of the total number of mines in the country, and in which it has heretofore been impossible for a truck of this type to be used. It will also be observed that due to my improved supporting mechanism it is possible to support the mining machine over the bottom and beyond the end of the track when used with either a room and pillar machine or a machine of the type wherein the machine cuts on its support, with both greatly increased stability and facility. More particularly, it will be observed that in my improved mechanism a stable supporting means is provided having substantial and relatively wide contact with the bottom at points spaced on opposite sides of the center line and beneath the outer position of the mining machine on its support. It will also be observed that this mechanism is automatically set as the machine moves out, thereby eliminating the necessity for the operator's setting manually and laboriously two or more jacks beneath the front or rear end of the machine before the latter can be moved forward on its support. Attention is also directed to the fact that through the use of my improved mechanism which automatically compensates for variations in the level of the mine bottom and provides a stable support under all conditions, all necessity for manual adjustment of the jacks heretofore used during the setting of the same is avoided. In other words, it will be observed that due to my improved construction it is possible for a machine of either the room and pillar or the mounted cutter type to be run into a place in either a room or an entry and be automatically supported and extended beyond the end of the rails and close to the face without the necessity for the operator's setting or adjusting any supports whatsoever, and this regardless of the level of the mine bottom. Conversely, it will be observed that after either a room or an entry has been cut, it is possible to return the machine to its transport position and start it along the track toward the next

place without the removal of any jacks, thereby further increasing the facility and speed of mining. Due to my improved construction including the swivel, slide, and feed chain connections, it will also be observed that means are provided to facilitate the loading of a room and pillar machine. These and other advantages of my improved construction will, however, be clearly apparent to those skilled in the art.

While I have in this application specifically described several embodiments which my invention may assume in practice, it is to be understood that these forms are used for purposes of illustration only and that the invention may be further modified and embodied in various other forms without departing from its spirit or the scope of the appended claims.

What I claim as new and desire to secure by Letters Patent is:

1. In a mining apparatus, an upstanding support, cutting mechanism thereon movable relative thereto, and supplemental movable supporting means for said support controlled by movement of said mechanism.
2. In a mining apparatus, an upstanding support, cutting mechanism thereon movable rectilinearly relative thereto, and supplemental movable supporting means for said support controlled by movement of said mechanism.
3. In a mining apparatus, an upstanding support, cutting mechanism thereon movable relative thereto, and supplemental operatively connected movable supporting means for said support set in operation upon movement of said mechanism.
4. In a mining apparatus, a non-collapsible support, cutting mechanism thereon movable relative thereto, and supplemental operatively connected supporting means for said support automatically movable to operative position as said mechanism moves in one direction.
5. In a mining apparatus, a non-collapsible support, cutting mechanism thereon movable relative thereto, and supplemental operatively connected supporting means for said support automatically movable to inoperative position as said mechanism moves in one direction.
6. In a mining apparatus, a non-collapsible support, cutting mechanism thereon movable reversely relative thereto, and supplemental operatively connected supporting means for said support automatically movable to and from operative position as said mechanism moves in opposite directions.
7. In a mining apparatus, a horizontally disposed frame, cutting mechanism thereon movable longitudinally thereof, supporting means for said frame, and cooperating supporting means for said frame controlled by movement of said mechanism.
8. In a mining apparatus, a horizontally disposed frame, cutting mechanism thereon movable longitudinally thereof, supporting means for said frame, and cooperative supporting means for said frame automatically movable into operative position as said mechanism moves in one direction.
9. In a mining apparatus, a horizontally disposed frame, cutting mechanism thereon movable longitudinally thereof, supporting means for said frame, and cooperating supporting means for said frame automatically movable into inoperative position as said mechanism moves in one direction.
10. In a mining apparatus, a frame relative to which a member is adapted to be moved, supporting means for said frame maintaining the same in elevated position in a horizontal plane, supplementary movable supporting means for said frame, and means automatically controlled by movement of a member movable relative to said frame controlling one of said supporting means.
11. In a mining apparatus, a frame relative to which a member is adapted to be moved, supporting means for said frame maintaining the same in elevated position in a horizontal plane, supplementary movable supporting means for said frame, and means automatically controlled by movement of a member movable relative to said frame controlling said supplementary supporting means.
12. In a mining apparatus, a frame, supporting means for the opposite ends thereof maintaining said frame in a horizontal plane, a supplemental supporting means, cutting mechanism movable longitudinally of said frame, and means controllable thereby controlling the position of one of said supporting means.
13. In a mining apparatus, a frame, supporting means for the opposite ends thereof, a supplemental supporting means, cutting mechanism carried by and movable longitudinally of said frame, and means operable in timed relation with said mechanism controlling the position of one of said supporting means.
14. In a mining apparatus, a wheel supported frame movable freely over a track-way and having one end disposable over the mine bottom, cutting mechanism carried by and movable relative to said frame, and supplemental movable means controlled by said mechanism for supporting said end of the frame.
15. In a mining apparatus, a wheel supported horizontal frame having one end disposable beyond the end of a mine track, cutting mechanism carried by and movable relative to said frame, and supplemental movable means having its movement controlled by said mechanism for supporting said end of the frame.

16. In a mining apparatus, a wheel supported horizontal frame having one end extending substantially beyond the wheels thereof, and supplemental movable supporting mechanism for said end having its movement controlled by movement relative to the frame of a member movable relative to said frame. 70
17. In a mining apparatus, a wheel supported horizontal frame having one end extending substantially beyond the wheels thereof, and supplemental movable supporting mechanism for said end automatically adjustable as to height and having its movement controlled by movement relative to the frame of a member movable relative to said frame. 75
18. In a mining apparatus, a wheel mounted frame movable freely over a track-way, cutting mechanism thereon movable relative thereto, and supplemental cooperating means automatically actuated to support said frame as said mechanism moves relative thereto. 80
19. In a mining apparatus, a wheel mounted frame movable freely over a track-way, cutting mechanism thereon movable relative thereto, and supplemental cooperating means automatically actuated to support one end of said frame as said mechanism moves relative thereto. 85
20. In a mining apparatus, a guiding frame, a truck beneath one end thereof movable freely over a trackway, a mining machine carried by and movable longitudinally of said frame, and supplemental supporting mechanism for said frame adjustable as to height and controlled by movement of said machine. 90
21. In a mining apparatus, a support having a fixed relation to the horizontal and disposed in a horizontal plane, cutting mechanism thereon movable relative thereto, and automatically cooperating supplemental supporting means for said support of variable effective height. 100
22. In a mining apparatus, a support having a predetermined relation to the horizontal and disposed in a horizontal plane, cutting mechanism thereon movable relative thereto, and automatically cooperating supplemental supporting means for said support of automatically variable effective height. 105
23. In a mining apparatus, a wheel mounted frame having front and rear wheels, a member thereon movable relative thereto, and supplemental means automatically adjustable as to height actuated to support said frame as said member moves relative thereto. 110
24. In a mining apparatus, a wheel supported frame having front and rear wheels, cutting mechanism thereon movable relative thereto, and supplemental automatically cooperating supporting means for said frame engageable with the bottom at points on opposite sides of the frame center line and controlled by the position of said cutting mechanism. 115
25. In a mining apparatus, a support maintained in a definite relation to the horizontal and disposed in a horizontal plane, cutting mechanism movable over the same, a member movable therewith, and supplemental movable supporting mechanism for said support controlled by said member. 120
26. In a mining apparatus, a support maintained in a definite relation to the horizontal and disposed in a horizontal plane, cutting mechanism movable over the same, a member movable therewith, and cam operated supplemental supporting mechanism for said support actuated by said member. 125
27. In a mining apparatus, an upstanding support disposed in a horizontal plane, cutting mechanism movable thereon, supplemental foldable supporting mechanism for said support, and automatically actuated mechanism controlling the position thereof. 130
28. In a mining apparatus, an upstanding frame disposed in a horizontal plane, a member movable thereon, and supplemental normally operative supporting mechanism for said frame releasable by said member. 135
29. In a mining apparatus, an upstanding frame disposed in a horizontal plane, a member movable thereon, and foldable supplemental supporting mechanism for said frame folded and unfolded by said movable member. 140
30. In a mining apparatus, an upstanding frame disposed in a horizontal plane, a member movable thereon, and foldable normally operative supplemental supporting mechanism for said frame folded and unfolded by said movable member. 145
31. In a mining apparatus, an upstanding frame disposed in a horizontal plane, a mining machine thereon movable relative thereto, a supplemental pivotally mounted supporting member therefor beneath the same controlled by movement of said machine, and automatically operative means for holding the same in a plurality of positions. 150
32. In a mining apparatus, an upstanding frame, a mining machine thereon movable relative thereto, a supplemental pivotally mounted supporting means therefor beneath the same controlled by the position of said machine, and automatically operative gravity actuated means for holding the same in a plurality of positions. 155
33. In a mining apparatus, an upstanding frame, pivotally mounted supporting means therefor beneath the front end of the same, and automatically operative means for holding the same in a plurality of angular positions with respect to the horizontal. 160
34. In a mining apparatus, a supporting frame, pivotally mounted supporting means beneath the front end of the same, and co- 165

operating dogging mechanism rigidly connecting the free end thereof with said frame in a plurality of positions.

35. In a mining apparatus, a supporting frame, pivotally mounted supporting means beneath the front end of the same, means including cooperating movable dogging mechanism rigidly connecting the free end thereof with said frame, and a controlling member 10 for said dogging mechanism.

36. In a mining apparatus, a supporting frame, pivotally mounted supporting means beneath the same, cooperating movable dogging mechanism rigidly connecting the free 15 end thereof with said frame, and a controlling member for said dogging mechanism having a portion engageable by a member movable over said frame.

37. In a mining apparatus, a supporting frame, supporting means including members beneath the same disposed in opposite directions and on opposite sides of the center line of said frame, and means acting on the free ends thereof for elevating the same into 25 folded position.

38. In a mining apparatus, a supporting frame, supporting means including members beneath the same disposed in opposite directions and on opposite sides of the center line 30 of said frame, and means including a pivoted member, acting on the free ends thereof for elevating the same into folded position.

39. In a mining apparatus, a supporting frame, supporting means including members beneath the same disposed in opposite directions and on opposite sides of the center line 35 of said frame and interlocking mechanism between said members, and means for releasing said mechanism and elevating said members into inoperative position.

40. In a mining apparatus, a frame, a member thereon movable relative thereto, supporting means for said frame retaining the same in a predetermined relation to the 45 horizontal and in a horizontal plane, supplemental supporting means therefor, mechanism for moving the latter into inoperative position as said member is moved, and cooperating means for holding the same in that 50 position.

41. In a mining apparatus, a guiding frame, a member thereon movable relative thereto, supporting means for said frame retaining the same in a predetermined relation to the horizontal and in a horizontal plane, supplemental supporting means therefor, mechanism for moving the latter into inoperative position as said member is moved, and cooperating means movable with 55 said member for holding the same in that position.

42. In a mining apparatus, a supporting frame having a predetermined relation to the horizontal, normally depending pivoted 60 and pivotally connected members disposed

beneath the front end of the same, mechanism for maintaining said members in a plurality of different angular relations, and means for folding said members beneath said frame.

43. In a mining apparatus, a supporting frame having a predetermined relation to the horizontal, normally depending pivoted and pivotally connected members disposed beneath the same, mechanism for maintaining said members in a plurality of different angular relations, and means controlled by a member movable over said frame for folding said members beneath the latter.

44. In a mining apparatus, a wheeled horizontal supporting frame having its bottom disposed substantially adjacent the axis of its wheels, means movable thereon, and supplemental supporting mechanism for said frame movable to and from operative position in timed relation with said movable means.

45. In a mining apparatus, a wheel supported frame movable freely over a trackway, a mining machine movable thereon, and supplemental supporting means automatically set in operative position before the center of gravity of said machine passes over the axis of the front wheels.

46. In a mining apparatus, a wheeled truck frame, and a laterally movable loading and unloading member reciprocably carried thereby and disposable thereon in a plane below the tops of the wheels thereof.

47. In a mining apparatus, a wheeled truck frame, a horizontally swinging machine loading and unloading member carried thereby, and means whereby the latter may be disposed thereon in a horizontal plane below the tops of the wheels thereof.

48. In a mining apparatus, a wheeled truck frame, and a tilttable and horizontally swinging machine loading and unloading member carried thereby and disposable thereon in a plane below the tops of the wheels thereof.

49. In a mining apparatus, a wheeled truck frame, and a tilttable and horizontally swinging machine loading and unloading member reciprocably carried thereby and disposable thereon in a plane below the tops of the wheels thereof.

50. In a mining apparatus, a wheeled truck frame, a tilttable and horizontally swinging machine loading and unloading member reciprocably carried thereby in a plane below the tops of the wheels, and means for reciprocating said member.

51. In a mining apparatus, a wheeled truck frame, a tilttable and horizontally swingable mining machine loading and unloading member disposable thereon in a plane below the tops of the wheels thereof, and means for driving the truck wheels from a mining machine on said tilttable member.

52. In a mining apparatus, a wheeled guiding frame, a support movable relative thereto guided thereby and disposed below the level of the tops of the wheels thereof, and a machine loading and unloading member carried on said support. 70
53. In a mining apparatus, a wheeled guiding frame, a support guided thereby and disposed below the level of the top of said wheels, and means for laterally swiveling said support when it reaches a predetermined position on said frame. 75
54. In a mining apparatus, a wheeled guiding frame, a support guided thereby and disposed below the level of the top of said wheels, and means for laterally swiveling said support and locking it against longitudinal movement when it reaches a predetermined position on said frame. 80
55. In a mining apparatus, a wheeled guiding frame, a machine receiving member guided thereon and disposed below the level of the top of the wheels, and means for laterally swiveling said receiving member when it reaches a predetermined position on said frame. 85
56. In a mining apparatus, a wheeled machine receiving and guiding frame, a swivel member slidably mounted thereon, and a vertically tilttable machine loading member movable with said swivel member and disposed in a plane below the level of the top of the wheels. 90
57. In a mining apparatus, a wheeled machine receiving and guiding frame, a swivel member slidably mounted thereon, a vertically tilttable machine loading member movable with said swivel member, and feed member engaging means on said frame and on the rear end of said tilting member. 95
58. In a mining apparatus, a wheeled machine receiving and guiding frame, a swivel member slidably mounted thereon, a vertically tilttable machine discharging member on said swivel member, and feed member engaging means on said frame and on one side of the rear end of said tilting member. 100
59. In a mining apparatus, a wheeled machine receiving and guiding frame, a swivel member slidably mounted thereon, a tilting machine loading member movable with said swivel member, and feed member engaging means on said frame and on opposite sides of the rear end of said tilting member. 105
60. In a mining apparatus, a wheeled machine receiving and guiding frame, a swivel member slidably mounted thereon, a vertically tilttable machine loading member movable with said swivel member, and feed member engaging means on the opposite ends of said frame and on the rear end of said tilting member. 110
61. In a mining apparatus, a guiding frame, wheels therefor, the bottom of said guiding frame being disposed substantially 115
- in the plane of the axis of the wheels, a laterally swiveling machine carrying member movable thereon, and a mining machine carried on said carrying member with its bottom disposed beneath the top of said wheels. 70
62. In a mining apparatus, a guiding frame, wheels therefor, the bottom of said guiding frame being disposed substantially in the plane of the top of the wheel axles, a swivel mounted machine carrying member movable thereon, a mining machine carried thereon, and supplemental supporting means for said frame. 75
63. In a mining apparatus, a guiding frame, wheels therefor, the bottom of said guiding frame being disposed substantially in the plane of the top of the wheel axles, a swivel mounted machine carrying member movable thereon, a mining machine carried thereon, and supplemental supporting means for said frame operating in timed relation with the movement of said machine. 80
64. In a mining apparatus, a guiding frame, wheels therefor, the bottom of said guiding frame being disposed substantially in the plane of the top of the wheel axles, a swivel mounted tilttable machine carrying member movable thereon, a mining machine carried thereon, and supplemental supporting means for said frame operating in timed relation with the movement of said machine. 85
65. In a mining apparatus, a machine receiving frame, a truck therefor, truck driving mechanism on said frame, a machine on said frame movable into operative relation to said truck driving mechanism, and supplemental supporting means beneath the front end of said frame automatically movable into operative and inoperative position as said machine moves reversely relative to 100
- said truck driving mechanism. 105
66. In a mining apparatus, a wheel supported frame having a guiding surface disposed beneath the level of the top of the wheels, a tilting machine support movable relative thereto, a mining machine slidably in and with said support, supplemental supporting mechanism controlled by the movement of said machine, means for swiveling said support when the latter reaches a predetermined position on said frame, and means operatively connected to said machine for moving said support longitudinally and angularly and moving said machine relative to said support. 110
67. In a mining apparatus, a wheeled machine supporting frame having its front end extending beyond the front wheels thereof, a tilttable machine unloading and loading frame disposed at the front end thereof and movable to and from tilted position as a machine is unloaded therefrom and loaded thereon, respectively, and supplemental supporting mechanism for the front end of 115
- said supporting frame automatically set in 120
- 125
- 130

operative position prior to the unloading movement of said tilting frame and moved to inoperative position after the loading movement thereof.

- 5 68. In a mining apparatus, a rigid wheeled truck frame, a rigid machine receiving member overlying the axes of said wheels and having its machine supporting surface disposed in a plane adjacent said axes, said 10 member being tiltably and horizontally swiveled on said frame, and truck wheel driving mechanism on said frame including a member rotatable by a mining machine on said receiving member.
- 15 69. In a mining apparatus, a rigid wheeled truck frame, a rigid machine receiving member thereon tiltably and horizontally swiveled at points substantially midway between its ends and on the front of said frame, 20 truck wheel driving mechanism including a member rotatable by a mining machine on said receiving member, and a feed member abutment on the rear end of said frame.
- 25 70. In a mining apparatus, a rigid wheeled truck frame, a rigid machine receiving member thereon tiltably and horizontally swiveled at points substantially midway between its ends and on the front of said frame, truck wheel driving mechanism including 30 a member rotatable by a mining machine on said receiving member, and feed member abutments on the rear ends of said frame and receiving member.

35 71. In a mining apparatus, a wheeled truck, and a machine receiving frame tiltably mounted thereon having an open rear end and a longitudinally extending feed member receiving notch in the latter.

40 72. In a mining apparatus, a wheeled truck, and a mining machine receiving frame tiltably mounted thereon having an open rear end and a pair of longitudinally extending feed member receiving notches in the latter and on opposite sides of the center 45 line thereof.

50 73. In a mining apparatus, a wheeled truck, a machine receiving frame tiltably mounted thereon having an open rear end and a longitudinally extending feed member receiving notch in the latter, and a feed member abutment carried on said truck in rear of said frame.

55 74. In a mining apparatus, a wheeled truck, a machine receiving frame tiltably mounted thereon having an open rear end and a pair of laterally spaced longitudinally extending feed member receiving notches in the latter on opposite sides of the center line thereof, and a feed member abutment carried on said truck in rear of said frame.

60 75. In a mining apparatus, a wheeled truck, a machine receiving frame thereon swiveled on a vertical axis and tiltable about a transverse pivot, a feed member abutment 65 on the rear end of said frame, and a feed

member abutment on the rear end of said truck.

76. In a mining apparatus, a wheeled truck, a machine receiving frame thereon swiveled on a vertical axis and tiltable about 70 a transverse pivot, said frame having an open rear end and a feed member notch therein, and a feed member abutment carried on the rear end of said truck.

77. In a mining apparatus, a wheeled 75 truck, a horizontally movable vertically tiltable machine receiving frame thereon having a plurality of laterally spaced feed member abutments on its rear end, and a feed member abutment on the rear end of said truck. 80

78. In combination, a wheeled truck, a vertically tiltable horizontally swinging frame thereon, truck driving mechanism on said truck including a member driven by a moving part of a mining machine on said 85 frame, and self-contained means supported by said truck for utilizing the power of a mining machine when said frame is in a lateral position to move the machine onto 90 said frame and into operative relation to said member.

79. In a mining apparatus, a wheeled truck, a horizontally swinging vertically tiltable machine receiving frame thereon, and means for utilizing the power of a mining 95 machine when said frame is in a lateral position to tilt and swing said frame into alinement with said truck during movement of said machine relative to said frame.

80. In a mining apparatus, a wheeled truck, a horizontally swingable vertically tiltable machine receiving frame thereon, and means for utilizing the power of a mining machine when said frame is in a lateral 100 position to tilt and swing said frame into alinement with said truck during movement 105 of said machine relative to said frame and in one operation.

81. In a mining apparatus, a wheeled truck, a horizontally swingable vertically tiltable machine receiving frame thereon, and means whereby the flexible feeding member of a mining machine may be so connected to said frame and truck that the machine may be moved on to said frame and said frame tilted and swung into alinement 110 with the truck in one continuous operation. 115

82. In a mining apparatus, a wheeled truck, a horizontally swingable vertically tiltable machine receiving frame thereon, and means whereby the flexible feeding member of a mining machine may be successively connected to said frame and truck 120 to load the machine on the former and tilt the former and to swing said frame into alinement with the truck. 125

83. In a mining apparatus, a wheeled truck, a tiltable and horizontally movable machine receiving frame thereon, truck driving mechanism on said truck including 130

- a member meshing with a rotating part of a mining machine on said receiving frame, and power means for tilting said frame and swinging the same and a mining machine 45
6 thereon from angular relation into operative relation with said driving mechanism in one operation.
84. In a mining apparatus, a wheeled truck, a horizontally swingable vertically 50
10 tilttable machine receiving frame thereon having an open front end, a mining machine having a flexible feeding member and supported directly on said receiving frame and movable into and out of the end thereof, and 55
15 connections whereby when said machine is on the mine bottom and said frame is laterally disposed the power of the machine may be utilized to draw said machine on to said frame, tilt the latter, and swing the 60
20 same into alinement with said truck.
85. In a mining apparatus, a wheeled truck, a horizontally swingable vertically 65
25 tilttable machine receiving frame thereon having an open front end, a mining machine having a flexible feeding member and supported directly on said receiving frame and 70
30 movable into and out of the end thereof, loading and unloading abutments for said flexible member, and truck driving connections comprising intermeshing elements carried on said machine and on said truck at the rear end of said frame.
86. In a mining apparatus, a wheeled truck, a horizontally swingable vertically 75
35 tilttable machine receiving frame thereon having an open front end, a mining machine having a flexible feeding member and supported directly on said receiving frame and movable into and out of the end thereof, 80
40 loading and unloading abutments for said flexible member comprising abutments on the rear end of said truck and the opposite
- ends of said frame, and truck wheel driving mechanism on said truck adapted to be operatively connected to said mining machine. 45
87. In a mining apparatus, a wheeled truck, a horizontally swingable vertically 50
tilttable machine receiving frame thereon having an open front end, a mining machine having a flexible feeding member and supported directly on said receiving frame and 55
movable into and out of the end thereof, loading and unloading abutments for said flexible member comprising an abutment on the rear end of said truck and a plurality of laterally spaced abutments on each end of said frame, and truck wheel driving mechanism on said truck adapted to be operatively connected to said mining machine. 60
88. In a mining apparatus, a wheeled truck, a horizontally swingable vertically 65
tilttable machine receiving frame thereon having an open front end, a mining machine having a flexible feeding member and supported directly on said receiving frame and 70
movable into and out of the end thereof, loading and unloading abutments for said flexible member comprising an abutment on the rear end of said truck and a plurality of laterally spaced abutments on each end 75
of said frame, and truck wheel driving mechanism including intermeshing elements carried on the rear end of said machine and the rear end of said truck.
89. In a mining apparatus, a wheeled truck, a vertically tilttable machine receiving frame thereon, upstanding feed member abutments on the rear end thereof on opposite sides of the longitudinal center line thereof, and a feed member abutment carried on the rear end of said truck. 80

In testimony whereof I affix my signature.

MORRIS P. HOLMES.

Certificate of Correction.

Patent No. 1,641,430.

Granted September 6, 1927, to

MORRIS P. HOLMES.

It is hereby certified that error appears in the printed specification of the above-numbered patent requiring correction as follows: Page 1, line 32 and page 4, line 13, for the word "filler" read *pillar*; page 7, line 69, claim 8, for "cooperative" read *cooperating*; page 11, line 75, for the ordinal "11" read 77; and that the said Letters Patent should be read with these corrections therein that the same may conform to the record of the case in the Patent Office.

Signed and sealed this 18th day of October, A. D. 1927.

[SEAL.]

M. J. MOORE,
Acting Commissioner of Patents.
